Alexander Morrison, Troy, N. Y.
Letters Patent No. 169 dated 8th. March 1848.

The Schedule referred to in these Letters Patent and making part of the same. To all whom it may concern: Be it known that I, Alexander Morrison of Troy, in the County of Rensselaer and State of New York, have invented a new and useful design for an ornamental air-light Cooking Stove, and I do hereby declare that the accompanying drawings making part of this Specification are full and accurate delineations of a stove after my said design, Fig. A, being a perspective view, and Figs. 1, 2 and 3 being respectively the side, front and rear upon a larger scale to show the detail of ornament - Fig. 4 is a portion of the side hearth b, (see Fig. A) - a is a section of the door panel mouldings - In Figs. 2, 3 & 4, but one half the plate is exhibited, the remaining portion being similar to and symmetrical with that represented.

What I claim as my invention and desire to secure by letters Patent is the combination and arrangement of ornamental figures and forms exhibited in the accompanying drawings, forming an ornamental design for an air tight Cooking Stove.
